Specification for Design.

Patented Aug. 30, 1921.

Application filed April 12, 1921. Serial No. 460,813. Term of patent 3½ years.

To all whom it may concern:

Be it known that I, HENRY C. LLUFRIO, a citizen of the United States, residing at Providence, in the county of Providence and State of Rhode Island, have invented a certain new, original, and ornamental Design for a Collar-Holder, of which the following is a specification.

In the accompanying drawings which form a part of this specification

Figures 1 and 2 are a front elevation, and a plan view respectively of a collar holder embodying my design.

I claim:

The ornamental design for a collar holder, as shown.

HENRY C. LLUFRIO.
